UNITED STATES PATENT OFFICE.

GEORGE D. EIGHMIE, OF NEW YORK, N. Y.

GAS-ENGINE.

1,076,877.

Specification of Letters Patent.

Patented Oct. 28, 1913.

Application filed September 15, 1910. Serial No. 522,127.

To all whom it may concern:

Be it known that I, GEORGE D. EIGHMIE, of the borough of Manhattan, city, county, and State of New York, have invented certain new and useful Improvements in Gas-Engines, of which the following is a full, clear, and exact specification, such as will enable others skilled in the art to which it appertains to make and use the same.

10 My invention relates particularly to two-cycle gas engines of the base compression type, and it has for its object to secure an effectual scavenging of the cylinder and the introduction of the explosive charge properly in the working chamber without confusion with the burnt gases. This end is attained by a certain novel construction and organization of the engine, which will fully appear from this specification and be particularly pointed out in the claims. For this purpose, reference is now had to the accompanying drawings, which show one embodiment of my invention.

20 In these drawings:—Figure 1 is a vertical section of my improved engine; Fig. 2 is a sectional view taken on the line 2—2 of Fig. 1, looking in the direction of the arrow.

In these drawings, similar reference characters designate similar parts.

30 10 indicates the cylinder or working chamber of the engine, which is extended downward to form an inclosed base 11, through which extends the crank shaft 12 in the usual manner.

35 14 indicates the connecting rod and 15 the working piston of the engine, which is here shown as of the trunk type, adapted to overrun, in top center position, the admission port 16 and to overrun, in bottom center position, the exhaust ports 17.

40 To provide free inlet and outlet of the gases and prevent wire-drawing and throttling thereof, the inlet and exhaust ports 16 and 17 are caused to extend completely around the cylinder, thus providing an extremely large port area, conducive to high speed operation of the engine. Said ports are surrounded by manifold boxes, 18 and 19, the former having suitable connection 45 with the source of the explosive mixture and the latter having suitable connection with the means for disposing of the exhaust gases. The piston 15 is formed with a large central opening from which extends upwardly a tubular projection 20 which, with its ports 27 is termed a valve. This valve

20 fits snugly in a dome 21 rising from the cylinder head. This dome 21 and valve 20 have a sliding fit and form a gas-tight and air-tight joint between them. The interior of the valve 20 has a hollow plug 25 fitting snugly therein with its upper end somewhat enlarged so as to fit snugly in the dome 21, where it is above the valve 20. The plug 25 is fixed in place by a suitable pin or other means 29 and is provided with packing rings 26 to engage the inner walls of the valve 20 so as to make a gas-tight joint with the same. The lower end of the plug 25 is conical. The cylinder head of the cylinder 10 is enlarged or bulging, as shown at 28 so as to provide a chamber to receive gas under pressure from the crank case 11 through the ports 27 when the piston 15 is at the lower limit of its movement.

50 In view of the foregoing description, the operation of my improved engine will be readily understood.

Assuming the parts to be as shown in Fig. 1 of the drawings and the spark plug or other igniting device in condition for use, the cycle is as follows: The explosive mixture of air and gas passes through the admission ports 16 into the crank case. The piston 15 is then lowered and this mixture 55 is thereby compressed. As soon as the mixture is fully compressed and the piston 15 is at the bottom of its movement, the charge, which has just been exploded, escapes through the ports 17, and the fresh mixture 60 in the crank case escapes through the ports 27 into the space above the piston 15 and more particularly into the enlarged part 28. This fresh gas, by passing as above described, into the top of the cylinder, forces 65 the spent gases to escape at the bottom thereof through the ports 17, so that the cylinder is effectually scavenged. The piston 15 then rises and compresses the explosive mixture 70 and at the proper time this mixture is exploded, the piston is driven downwardly and at the end of the stroke the charge is exhausted through the ports 27 and forced out by the incoming charge as above described.

75 What I claim is:

1. A two-cycle gas engine adapted to have admission and exhaust respectively at its working cylinder ends, a working piston with a port through it, a tubular valve integral with said piston and open at its ends carried by said piston, a housing in which

the valve operates, a valve box having a conical lower end mounted rigidly in said housing, said valve being adapted to embrace said box in its reciprocatory movement and said housing being adapted to embrace said valve.

2. A two-cycle gas engine adapted to have admission and exhaust respectively at its working cylinder ends, a working piston 10 with a port through it, a tubular valve integral with said piston and having its upper end terminating in fingers and a housing in which the valve operates, a valve box

having a conical lower end, said valve being adapted to have air-tight connection with 15 said housing and said valve box during its reciprocatory movement and to permit admission at the bottom center piston position.

In testimony whereof I have signed my name to this specification in the presence 20 of two subscribing witnesses.

GEORGE D. EIGHMIE.
